ALARM HOUSING

Ellsworth R. Danz, La Salle, Ill., William H. Featherly, Gadsden, Ala., and Roman J. Szalek, La Salle, Ill., assignors to General Time Corporation, Thomaston, Conn.

Filed Apr. 10, 1974, Ser. No. 459,593

Term of patent 14 years

Int. Cl. D10—06; D13—03
U.S. Cl. D10—121

FIG. 1.

FIG. 2.

FIG. 3.

FIG. 4.

FIG. 1 is a front perspective view of an alarm housing showing our new design;

FIG. 2 is a rear perspective of the structure of FIG. 1;

FIG. 3 is a bottom plan view of the structure of FIG. 1; and

FIG. 4 is a left side elevation view of the structure of FIG. 1.

We claim:

The ornamental design for an alarm housing, substantially as shown.
